(57) **CLAIM**

The ornamental design for a payment terminal as shown and described.

DESCRIPTION

1.1 : Top

1.2 : Front

1.3 : Back

1.4 : Bottom

1.5 : Right

1.6 : Left

1.7 : Perspective

The payment terminal has four beveled corners as well as a large screen and a keypad.

The broken lines in the drawings depict portions of the payment terminal that form no part of the claimed design.
